(57) **CLAIM**

The ornamental design for a cosmetic device, as shown and described.

DESCRIPTION

FIG. 1 is a perspective view of my new design, showing a cosmetic device;

FIG. 2 is another perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is an enlarged partial view showing a portion of the cosmetic device marked 9 in FIG. 2.

The dash-dot broken lines shown in FIGS. 2 and 9 are for the purpose of showing enlarged areas, and form no part of the claimed design.

The line shading in FIGS. 1-9 represents contour and not surface ornamentation.
